[57] CLAIM

The ornamental design for a crib footboard, as shown and described.

DESCRIPTION

FIG. 1 is a front elevation view of a crib footboard according to the invention;

FIG. 2 is a side elevation view thereof, the opposite side being a mirror image thereof;

FIG. 3 is a top plan view thereof;

FIG. 4 is a sectional view taken along the plane of line 4—4 in FIG. 1;

FIG. 5 is a sectional view taken along the plane of line 5—5 of FIG. 1;

FIG. 6 is a sectional view taken along the plane of line 6—6 in FIG. 1, each pair of outside spindles having the same cross section;

FIG. 7 is a sectional view taken along the plane of line 7—7 in FIG. 1, each of the three middle spindles having the same cross section;

FIG. 8 is a sectional view taken along the plane of line 8—8 in FIG. 1; and

FIG. 9 is a sectional view taken along the plane of line 9—9 in FIG. 1.
